KEY-SET CIRCUIT

James B. McKim, East Orange, N. J., assignor to
Bell Telephone Laboratories, Incorporated, New
York, N. Y., a corporation of New York

Application December 31, 1940, Serial No. 372,533

7 Claims. (Cl. 179—27)

This invention relates to telephone exchange systems and more particularly to systems in which connections are established between subscribers' lines terminating in different offices over toll trunks by dial switching mechanism under the control of a toll operator.

In the establishment of connections to offices of a dial switching area for which toll rates should be assessed for service, it is customary for a calling subscriber in such an office who desires a connection with another subscriber at a remote point to dial a number whereby a connection is first obtained with a toll operator who then proceeds to set up the desired connection and to supervise the assessment of the required toll charge.

In some cases it is desirable to include in an exchange area offices which are located on the fringe of such area and to control the extension of toll connections to lines terminating in such offices from toll operators' positions located in the main exchange area. Under these conditions, the trunks extending from the toll operator's position to the fringe offices might be of considerable length and since the register sender equipment would be located in the terminating office, the transmission of key-pulsing impulses over such a long trunk for setting the digit registers of a selected register sender by direct current impulses of different polarity and current strength as has heretofore been proposed, might prove to be unreliable.

It has been proposed as disclosed in the application of P. B. Murphy, Serial No. 372,560, filed concurrently herewith, to transmit digit impulses over long trunks for registration in the registers of a sender located at a distant terminating office by providing each toll operator's position circuit with a ten button key-set common to the cord circuits of the position which becomes associated with a cord circuit when the operator takes it for use; by providing equipment common to all of the operators' positions for generating a plurality of alternating current frequencies, for combining such frequencies in different combinations of two frequencies each and for applying them to the keys of the key-set and to the contacts of the key-pulsing signaling relay and to the contacts of a start relay also provided at each operator's position; and by providing receiving equipment associable with the terminating sender for receiving the signal impulses, for translating them and for controlling the sender in accordance therewith.

The present invention relates more particularly to key-set circuits applicable to systems of the type disclosed in the application above referred to and has for its object to enable the more reliable and efficient functioning of a toll operator's position in the establishment of toll connections to subscribers' lines terminating in offices of the dial switching character.

To attain this object each operator's position 10 is provided with a ten button key-set, a start key, one or more key-pulsing keys and control relays. After the operator has extended a connection toward the terminating office by plugging into the jack of a trunk extending thereto 15 she operates a key-pulsing key at her position which causes the operation of a connecting relay and a key-pulsing relay whereby a signaling circuit is established from her key-set circuit over the talking conductors of the cord circuit and the selected trunk to the receiving equipment over 20 which circuit a preliminary key-pulsing signal of two particular frequencies generated by a signaling current supply circuit, common to all operators' positions, is transmitted during the time that the key-pulsing key is depressed and for an interval thereafter as predetermined by the slow-releasing characteristic of the key-pulsing relay. The operation of the key-pulsing relay also 25 operates an additional key-set disconnect relay which locks under the control of a start relay to maintain the connecting relay operated until after the subsequent operation of the start relay. After the termination of the key-pulsing signal following the release of the key-pulsing relay, a 30 lamp is lighted at the position as a signal to the operator that she may then proceed to key the digits of the wanted line number on the keys of her key-set.

The ten keys of the key-set are so connected 40 to the signaling current supply circuit that the depression of different ones of such keys is instrumental in transmitting signals comprising different combinations of two frequencies each. After the operator has completed the keying of 45 the digits of the wanted line number, she then operates the start key of her key-set circuit which causes the operation of the start relay to apply a further combination of two of the frequencies generated by the common equipment over the trunk to the receiving equipment as a signal that she has completed the keying of all digits. The start relay upon operating locks 50 under the control of the key-set disconnect relay, opens the locking circuit of such disconnect relay and closes a further locking circuit there-

for which is effective so long as the start key is held depressed. When, however, the start key is released, the key-set disconnect relay releases after a time interval determined by its slow-to-release characteristic in turn releasing the start relay to discontinue the start signal and releasing the connecting relay.

The invention having been considered in a general manner, reference may now be had for a clearer understanding thereof to the following detailed description taken in connection with the accompanying drawings in which:

Figs. 1, 2 and 3, taken together, with Fig. 2 at the right of Fig. 1 and Fig. 3 beneath Fig. 2 disclose one embodiment of the invention; Fig. 2 showing one of the cord circuits of an operator's position and a portion of the equipment common to all cord circuits of the position; Fig. 1 showing the grouping circuit and telephone circuit of the operator's position; and Fig. 3 showing the key-set circuit of the operator's position;

Figs. 5 and 6 taken together with Fig. 6 beneath Fig. 5 disclose a further embodiment of the invention; Fig. 5 showing one of the cord circuits of an operator's position and the operator's position grouping and telephone circuit common to all cord circuits of the position; and Fig. 5 showing the key-set circuit of the operator's position; and

Fig. 4 shows trunks outgoing from the toll operators' positions disclosed in Figs. 1 to 3, inclusive, and Figs. 5 and 6, and incoming at a distant terminating office in incoming selector switches indicated by the box in the upper right corner thereof, a link circuit represented by the box so labeled, a sender represented by the box so labeled and a key-impulsing receiving circuit represented by the box so labeled.

The operator's position key-set circuits of Figs. 3 and 6 are associative with signaling current supply circuits indicated by the boxes 350 and 650 of the type fully disclosed in the application of P. B. Murphy above referred to, and in the application of L. A. Meacham, Serial No. 372,557, filed Dec. 31, 1940. Toll connections may be completed by the cord circuits of Figs. 2 and 5 by the connection thereof with trunks extending to terminating offices. For controlling the completion of connections from such trunks, terminating equipment of the type disclosed in the application of P. B. Murphy hereinbefore referred to, may be employed although it is to be understood that other types of terminating equipment arranged to be responsive to alternating current signals of the type transmitted by the key-set circuits under consideration, might equally well be employed.

The embodiment of the invention disclosed in Figs. 1 to 3, inclusive, together with Fig. 4, will first be considered. It will be assumed that a toll connection is incoming to the operator's position and that the operator answers the call on the toll line by plugging the cord circuit plug 200 into the toll line jack 201. She then depresses the cord key 202 to the right or talking position. A circuit is thereupon established for relay 203 extending from battery through the winding of relay 203, the alternate contacts of key 202, conductor 204 to ground at the inner lower normal contacts of relay 100 of the operator's telephone circuit. Relay 203 upon operating closes a circuit for relay 100 extending as traced from ground on conductor 204 over the alternate contacts of key 202, the No. 1 lower front

5 contacts of relay 203, conductor 205 to battery through the winding of relay 100. Relay 100 thereupon operates removing ground from conductor 204 to prevent another cord circuit relay, such as relay 203, from operating. With relay 101 operated, since the operator's telephone set 102 will have been plugged into the position jack to establish the circuit thereof extending from battery through its winding, the upper contacts of jack 103 to ground at the outer right back contact of relay 104, relay 100 closes the holding circuit for cord circuit relay 203 which may be traced from ground over its inner lower alternate contacts, the No. 1 upper front contacts of relay 101, conductor 105, the No. 1 upper front contacts of relay 203, the upper alternate contacts of key 202 to battery through the winding of relay 203. Thereby relay 203 individual to the cord circuit and relay 100 common to all 10 cord circuits of the position are held operated. Relay 203 splits the cord circuit and associates conductors 206 to 209, inclusive, with the cord circuit.

The operation of relay 100 connects the tip 25 and ring conductors 106 and 107 of the operator's headset circuit over its outer front contacts and the No. 2 upper and No. 1 lower contacts of relay 101 to conductors 108 and 109 extending to the left or monitoring contacts of the 30 key 202 and at its inner upper back contact disconnects the winding of relay 110 from conductor 111. If at this time the key 202 of another cord circuit of the operator's position is operated to the left or monitoring position, the operator 35 will be able to talk or listen on both cord circuits but will be able to split, transfer or key-pulse on only the cord circuit, the talking key of which has been operated to the right or talking position.

Upon the operation of relay 203 a circuit is 40 also established from high resistance ground on the sleeve of jack 201 over the sleeve of plug 200, the No. 2 lower contacts of relay 203 to battery through the windings of relays 210 and 211. Relay 211 upon operating closes an obvious circuit for relay 212, but relay 210 being marginal does not operate at this time. At its inner upper front contact, relay 212 connects ground through high resistance 213 and over the No. 3 45 lower contacts of relay 203 to the rear cord supervisory lamp 214 to warm the lamp without lighting it thereby improving its flashing characteristic. At its lower back contact, relay 212 disconnects the tip of the answering plug 200 50 from the busy test conductor 215 which is connected over the No. 4 lower front contact of relay 101 through the winding of relay 112 to ground and through condenser 113 to ground through the primary winding of transformer 114 and thence inductively to the operator's headset 102. At its outer front contacts, relay 212 also establishes a talking circuit which may be traced from the tip of the plug 200 over the No. 5 upper 55 contacts of relay 203, conductor 296, the No. 2 upper back contact of relay 300, conductor 301, the lower right normal contacts of splitting key 216, the lower front contact of relay 212, the lower back contact of relay 217, conductor 115, the lower No. 5 contacts of relay 101, conductor 107, through the lower windings of repeating coil 116, inductively coupled to the operator's headset transmitter, and over the back contacts of relay 110 to the operator's headset receiver, thence returning over conductor 106, the No. 3 upper 60 contacts of relay 101, conductor 117, the upper contacts of relay 203, conductor 205 to battery through the winding of relay 100. Relay 100 thereupon operates removing ground from conductor 204 to prevent another cord circuit relay, such as relay 203, from operating. With relay 101 operated, since the operator's telephone set 102 will have been plugged into the position jack to establish the circuit thereof extending from battery through its winding, the upper contacts of jack 103 to ground at the outer right back contact of relay 104, relay 100 closes the holding circuit for cord circuit relay 203 which may be traced from ground over its inner lower alternate contacts, the No. 1 upper front contacts of relay 101, conductor 105, the No. 1 upper front contacts of relay 203, the upper alternate contacts of key 202 to battery through the winding of relay 203. Thereby relay 203 individual to the cord circuit and relay 100 common to all 10 cord circuits of the position are held operated. Relay 203 splits the cord circuit and associates conductors 206 to 209, inclusive, with the cord circuit.

back contact of relay 217, the upper front contact of relay 212, the upper right normal contacts of splitting key 216, conductor 302, the No. 3 lower back contact of relay 300, conductor 209, the No. 5 lower contacts of relay 203 to the ring of plug 200. The operator is now enabled to receive instructions over the toll trunk for the further extension of the connection.

Having received instructions and it being assumed that a connection is desired with a subscriber's line which terminates in a dial switching office accessible over a group of trunks of which one is disclosed in the upper portion of Fig. 4, the operator proceeds to test such trunks by touching the tip of plug 224 to the sleeves of the trunk jacks. A circuit is thereupon established from the tip of plug 224 over the No. 4 upper contacts of relay 203, conductor 208, the No. 4 upper back contact of relay 303, conductor 304, the lower left normal contacts of splitting key 216, the lower back contact of relay 218, conductor 215, thence as previously traced to ground through the winding of relay 112 and through the primary winding of transformer 114. It will be assumed that the trunk terminating in jack 400 tests idle and that the operator on receiving no busy click in her headset inserts the plug 224 into jack 400. A circuit is thereupon established from ground through the high and low resistance windings of sleeve relay 401 in series over the sleeves of jack 400 and plug 224, the No. 3 upper alternate contacts of relay 203 to battery through the windings of relays 219 and 220. Sleeve relay 401 operates in this circuit establishing an obvious circuit for relay 402 which operates establishing a loop circuit over the two-conductor trunk extending to the terminating office and terminating thereat in an incoming selector. This loop circuit may be traced from battery at the terminating office through the lower winding of relay 403, the lower back contact of relay 404, the lower left winding of repeating coil 405 over the interoffice trunk conductor 406, the lower right winding of repeating coil 407, the contacts of relay 402, the winding of relay 409, the upper right winding of coil 407, trunk conductor 409, the upper left winding of repeating coil 405, the upper back contact of relay 404 and through the upper winding of relay 403 to ground. Relays 403 and 408 both operate, relay 403 closing an obvious circuit for relay 410 and relay 408 connecting direct ground through the upper or low resistance winding of relay 401 to the previously traced sleeve circuit thereby operating both relay 219 and relay 220 at the operator's position circuit.

Relay 410 upon operating establishes an operating circuit for relay 404 extending from battery through the winding thereof, over the back contact of relay 411 to ground over the upper contacts of relay 410 whereupon relay 404 operates to open the previously traced loop circuit through the windings of relays 403 and 408. Relay 403 does not release, however, being held operated in a local circuit through both of its windings and over the front contact of relay 404. Relay 408, however, releases again removing low resistance ground from the trunk sleeve circuit thereby releasing marginal sleeve relay 219. Relay 219 therefore operates only momentarily and without effect at this time.

Relay 220 upon operating establishes an obvious circuit for relay 218 which at its upper front contact connects ground through high resistance 221 over the No. 2 upper contacts of relay 75

203 to the circuit of calling supervisory lamp 222 for warming such lamp without lighting it to improve its flashing characteristic and establishes a talking circuit from the tip conductor 5 412 of the outgoing trunk, over the tips of jack 400 and plug 224, the No. 4, upper front contact of relay 203, conductor 208, the No. 4 upper back contact of relay 303, conductor 304, the lower left contacts of splitting key 216, the inner lower front contact of relay 218, the lower back contact of relay 223, conductor 115, thence as traced to the operator's telephone circuit and returning over conductor 117, the upper back contact of relay 223, the inner upper front contact of relay 218, the upper left normal contacts of key 216, conductor 305, the No. 2 lower back contact of relay 303, conductor 207, the No. 4 lower front contact of relay 203 over the rings of plug 224 and jack 400 to the ring conductor 20 413 of the outgoing trunk. At its lower back contact relay 218 opens the busy test circuit previously traced.

Relay 410 upon operating also closes a circuit extending from battery through the winding of 25 relay 414, thence over the lower contacts of relay 410 over the normal or position 17 contacts of sequence switch cam 415 to ground, whereupon relay 414 operates, locks in a circuit from battery through its winding, over the lower contacts of relay 410 and to ground over its own lower contacts and connects ground to the start circuit for starting a preselected idle link circuit such as is represented by the box 416 and which is fully disclosed in the patent to J. F. Dahl 30 2,020,458 of Nov. 12, 1935, whereupon the trunk finder 417 of the link circuit is started in search of the calling trunk.

As soon as the trunk is found, the link circuit sequence switch is advanced thereby causing the 40 advance of the sequence switch of the incoming selector into position 18 and the selector 418 of the link circuit is started in search of an idle key-pulsing receiving circuit such as is indicated by the box 419. When the selector 418 45 finds an idle receiving circuit, a test relay in the link circuit operates to arrest the hunting movement of the selector and to advance the sequence switch of the link circuit. A circuit is thereupon established which may be traced in part 50 from battery through the lower winding of supervisory relay 420 in the incoming selector, through the lower right winding of repeating coil 405, over the contacts of sequence switch cam 421, over the ring talking conductor extending through 55 the link circuit to the receiving circuit 419, thence through the high and low resistance windings of a relay (not shown) returning over the tip conductor extending from the receiving circuit through the link circuit, over the contacts of cam 422 through the upper right winding of repeating coil 405 to ground through the upper winding of relay 420. Due to the inclusion of the high resistance winding of the relay in the receiving circuit, the marginal supervisory relay 420 does not operate. At the receiving circuit a condition is established which causes the sequence switch of the link circuit to advance to a position for starting the sender selector 423 in search of an idle sender such as is indicated by the box 424. When an idle sender has been seized by the link circuit, a signal is transmitted from such sender to the receiving circuit whereby the high resistance winding of the supervisory relay thereof becomes shunted and the super-

visory relay 420 in the incoming selector circuit thereupon operates.

Relay 420 upon operating closes the circuit of relay 411 which may be traced from battery through its winding and lower normal contacts, over the contacts of relay 420 to ground over the upper contacts of relay 410. Relay 411 locks over its lower alternate contacts to ground at the lower contacts of relay 414 and opens the circuit of relay 404 which releases to restore the 10 loop circuit through the winding of relay 408. Relay 408 now operates and reconnects low resistance ground to the sleeve of the trunk through the upper or low resistance winding of sleeve relay 401. In response to the increased current 15 now flowing over the sleeve circuit previously traced through the windings of relays 219 and 220, marginal relay 219 now operates to connect ground over its contacts through resistance 225, the No. 2 upper contacts of relay 203 to the supervisory lamp 222 whereupon such lamp lights as a signal to the operator that a sender has become associated with the extended connection.

Since the call is an inward call, the operator may depress the front cord key-pulsing key 306 as soon as she has plugged up the cord whereupon a circuit is established from ground over the No. 3 upper back contact of relay 300, conductor 311, lower front contact of relay 218, conductor 309, over the right contacts of key 306 thence in parallel through the winding of relay 307 and the non-inductive resistance 308 to battery and a circuit is also established from battery through the winding of relay 303, left contacts of key 306, conductor 309, lower contacts of relay 218, conductor 311 to ground at the No. 3 upper back contact of relay 300. Relays 307 and 303 both operate, relay 307 upon operating extending its operating ground over its lower contact, the upper back contact of relay 314 and the upper front contact of relay 307 to battery through the winding of relay 312. Relay 312 thereupon operates and locks itself from ground on conductor 309, over the No. 1 upper contacts of relay 303, over its own upper contacts, the normal contacts of relay 313 and through its own inner lower front contact and winding to battery and extends this locking circuit from its upper contacts through the No. 1 lower contacts and winding of relay 303 to battery. Relay 303 upon operating causes lamp 315 to light in a circuit through resistance 316 and over its No. 3 upper contacts and at its No. 4 lower contacts prepares the circuit for relay 314. Relay 307 is now held operated under the control of relay 314 over a circuit extending from battery through its winding and outer lower contact, over the upper back contact of relay 314 and the No. 1 upper contact of relay 303 to ground on conductor 309.

As soon as a sender has become connected to the link circuit and such connection has been signaled by the operation of sleeve relay 219, a circuit is established from ground over its contacts, conductor 348, the No. 4 lower contacts of relay 303, the inner lower contacts of relay 307 to battery through the winding of relay 314. Relay 314 operates, opening the locking circuit of relay 307 at its upper back contact and establishing a circuit over which a key-pulsing signal is transmitted which may be traced in part from the signaling current supply circuit 350, over conductor 318, through resistance 320, the upper front contact of relay 314, through the right windings of repeating coil 317, the lower front contact of relay 314, resistance 321 and conductor 319, to the 75 desired line number on the key-set 310 and first

supply circuit 350. With relay 303 operated, the current impressed upon the left windings of repeating coil 317 is transmitted to the receiving circuit over the cord circuit and trunk, by way of a circuit which may be traced from the upper terminal of the left windings of repeating coil 317 over the No. 4 upper front contact of relay 303, conductor 208, the No. 4 upper front contact of relay 203, tips of plug 224 and jack 400, tip trunk conductor 412 through the left windings of repeating coil 407 returning over trunk conductor 413, rings of jack 400 and plug 224, the No. 4 lower front contact of relay 203, conductor 207, the No. 2 lower front contact of relay 303, to the lower terminal of the left windings of repeating coil 317. The current is further inductively transmitted over conductors 406 and 409 of the interoffice trunk through the right windings of repeating coil 407 and the left windings of repeating coil 405 and is inductively transmitted to the key-pulsing receiving circuit 419, through the link circuit 416. Following the operation of relay 314 and the opening of the holding circuit of relay 307 thereby, relay 307 releases after a predetermined interval if the key-pulsing key 306 has been released, and relay 307 upon releasing causes the release of relay 314 to terminate the key-pulsing signal. With both relays 307 and 314 released a circuit is established from ground over the lower contacts of relay 312, the lower back contact of relay 314 and the upper back contact of relay 307 to battery through lamp 360 which is lighted as a signal to the operator that she may proceed with the keying of the desired line number on the key-set 310.

As previously stated, signaling current of six frequencies is applied from the circuit indicated by the box 350 disclosed in the lower portion of Fig. 3. The six frequencies are generated by six vacuum tube oscillator circuits and are applied in different combinations of two frequencies each to twelve pairs of signaling conductors, shown extending upwardly from the box 350, by equipment fully disclosed in the aforementioned application of P. B. Murphy. One of the combinations of frequencies is employed in the transmission of the preliminary key-pulsing signal previously referred to, ten of the combinations of frequencies are employed in the transmission of the digit values 0 to 9, inclusive, and one of such combinations is employed in the transmission of a final start signal. Preferably the frequencies are of 700, 900, 1100, 1300, 1500 and 1700 cycles, respectively and are applied in the combinations set forth in the following table for the several signals above mentioned:

Frequency	Code signals											
	0	1	2	3	4	5	6	7	8	9	KP	ST
1,700-----											x	x
1,500-----			x	x	x						x	x
1,300-----		x	x	x	x	x						
1,100-----	x	x	x	x	x	x	x	x	x			
900-----	x	x	x	x	x	x	x	x	x	x		
700-----	x	x	x	x	x	x	x	x	x	x		

At the receiving circuit, the key-pulsing signal of the two frequencies 1300 and 1700 is instrumental in preparing the receiving circuit to receive signals transmitted through the subsequent operation of the keys of the key-set 310. It will be assumed that the number of the desired line is 2369 and that the operator after seeing the lighted lamp 360, proceeds with the keying of the desired line number on the key-set 310 and first

momentarily operates the digit key 328 of her key-set to cause the transmission of a signal for the thousands digit 2. Referring to the preceding table it will be noted that for this digit the signaling supply circuit 350 supplies current of the two frequencies 900 and 1300 cycles to the circuit which may be traced from conductor 322, through resistance 324, the left contacts of the depressed key 328, over the inner upper back contact of relay 314, through the right windings of repeating coil 317, over the inner lower back contact of relay 314, the right contacts of key 328, resistance 325 thence over conductor 323 to the supply circuit 350 so long as the key 328 is held depressed. As before this signaling current is inductively impressed over the windings of repeating coil 317 and the circuits previously traced and is effective at the receiving circuit to cause the registration of the digit 2 on the thousands register of the associated sender 424.

The operator will next momentarily depress the digit key 329 to cause the transmission of a signal for the hundreds digit 3. Referring to the preceding table, it will be noted that for this digit the signaling supply circuit 350 supplies current of the two frequencies 1300 and 1500 cycles to the circuit which may be traced from the supply circuit 350, over conductor 326, through resistance 327 over the left contacts of the depressed key 329, over the inner upper back contact of relay 314, through the right windings of repeating coil 317, over the inner lower back contact of relay 314, over the right contacts of key 329, through resistance 330 and over conductor 331 to the supply circuit 350 so long as the key 329 is held depressed. As before this signaling current is inductively impressed over the windings of repeating coil 317 and the circuits previously traced and is effective at the receiving circuit to cause the registration of the digit 3 on the hundreds register of the associated sender.

The operator will next momentarily depress the digit key 332 to cause the transmission of a signal for the tens digit 6. Referring to the preceding table, it will be observed that for this digit the signaling supply circuit 350 supplies current of the two frequencies 700 and 1100 cycles to the circuit which may be traced from conductor 333, through resistance 334 over the left contacts of the depressed key 332, over the inner upper back contact of relay 314, through the right windings of repeating coil 317, over the inner lower back contact of relay 314, the right contacts of key 332, through resistance 335 and over conductor 326 to the supply circuit 350 so long as the key 332 is held depressed. As before, this signaling current is inductively impressed over the windings of repeating coil 317 and the circuits previously traced and is effective at the receiving circuit to cause the registration of the digit 6 on the tens register of the associated sender.

The operator will next momentarily depress the digit key 337 to cause the transmission of a signal for the units digit 9. Referring to the preceding table it will be seen that for this digit the signaling supply circuit 350 supplies current of the two frequencies 700 and 1500 cycles to the circuit which may be traced from conductor 338, through resistance 339 over the left contacts of the depressed key 337, over the inner upper back contact of relay 314, through the right windings of repeating coil 317, over the inner lower back contact of relay 314, the right contacts of key 337, through resistance 340 and over conductor 341 to the supply circuit 350 so long as the key 337 is held

depressed. As before, this signalling current is inductively impressed over the windings of repeating coil 317 and the circuits previously traced and is effective at the receiving circuit to cause the registration of the digit 9 on the unit register of the associated sender.

Had the operator keyed digits having values other than those discussed, signals of combined frequencies would have been transmitted in accordance with the preceding table and in the manner previously described.

Following the keying of the last or units digit on the key-set 310, the operator momentarily depresses the start key 342 thereby closing an obvious circuit over the alternate contacts of such key for start relay 313 which operates and locks over its inner upper front contact to ground at the lower front contact of relay 312 and at its upper transfer contacts transfers the holding circuit for relay 312 from ground at the No. 3 upper back contact of relay 300 to ground over the left contacts of key 342 so that relay 312 is now maintained operated under the control of key 342. Relay 313 also establishes a new holding circuit for relay 303 extending from battery through the winding of such relay, over the No. 1 lower contacts thereof, the upper contacts of relay 313, the No. 1 upper contacts of relay 303, conductor 309, the lower contacts of relay 218 and conductor 311 to ground at the No. 3 upper back contact of relay 300. At its lower front contact relay 313 connects non-inductive resistance 343 in parallel with the winding of relay 312 to render it slow to release and at its other lower front contacts establishes a signaling circuit from the signaling supply circuit 350 over conductor 344, through resistance 345, the inner lower front contact of relay 313, over the inner lower back contact of relay 314, through the right windings of repeating coil 317, over the inner upper back contact of relay 314, the middle lower front contact of relay 313, resistance 346 and conductor 347 to the signaling supply circuit 350. Hence in accordance with the preceding table, current of the two frequencies 1500 and 1700 cycles is supplied to this circuit and current of such frequencies is inductively impressed over the windings of repeating coil 317 and the circuits previously traced and may be effective at the receiving circuit to inform the sender that no further digit signals are to be expected.

As soon as the operator releases the key 342, relay 312 releases followed after an interval by the release of relays 313 and 303. The operator's key-set circuit is now restored to its normal condition. Since the present invention does not involve the supervisory features of the cord circuit and of the position circuit, no detailed description thereof will be given herein.

Should the operator desire to key-pulse out over the rear cord plug 200 of her cord circuit she would operate the rear cord pulsing key 354 instead of the key-pulsing key 306. Upon the operation of key 354, relay 307 is operated as before and a circuit is established for relay 300 which may be traced from battery through its winding, over the left contacts of key 354, conductor 355, the inner lower contacts of relay 212 and conductor 356 to ground at the No. 2 upper back contact of relay 303. Relay 307 upon operating extends its operating ground over its lower contacts, the upper back contact of relay 314 and the upper front contact of relay 307 to battery through the winding of relay 312. Relay 312 thereupon operates and locks itself from

ground on conductor 355 over the No. 1 upper contacts of relay 300, over its own upper contacts, the normal contacts of relay 313 and through its own inner lower front contact and winding to battery and extends this locking circuit from its upper contacts through the No. 1 lower contact and winding of relay 300 to battery. Relay 300 upon operating closes a circuit for lamp 357 through resistance 316 and over its No. 4 upper contacts and at its No. 4 lower contacts prepares the circuit for relay 314. Relay 307 is now held operated under the control of relay 314 over a circuit which may be traced from battery through its winding and outer lower contact over the upper back contact of relay 314 and the No. 1 upper contacts of relay 300 to ground on conductor 355. When thereafter relay 210 operates to indicate that a receiving circuit and sender have become attached to the trunk with which cord plug 200 has been connected, the circuit of relay 314 may be traced from ground over the contacts of relay 210, conductor 349, the No. 4 lower contacts of relay 300, over the inner lower contacts of relay 307 to battery through the winding of relay 314. Relay 314 thereupon operates to apply the key-pulsing signaling current over conductors 318 and 319 and through the right windings of repeating coil 317 as previously described, which circuit is inductively connected to a circuit which may be traced in part from the tip of plug 200 over the No. 5 upper contacts of relay 203, conductor 206, the No. 2 upper front contact of relay 300, through the left windings of repeating coil 317, the No. 3 lower front contact of relay 300, over conductor 209 and the No. 5 lower contacts of relay 203 to the ring of plug 200. Relay 314 upon operating also opens the holding circuit of relay 307 which releases after an interval opening the circuit of relay 314 which then releases to discontinue the key-pulsing signal. From this point the key-set circuit functions in the manner previously described except that with relay 300 operated rather than relay 303, all of the keyed digit signals and the final start signal are transmitted over the plug 200.

The embodiment of the invention disclosed in Figs. 5 and 6 will now be considered. It will be assumed that a toll call is incoming to the operator's position and that the operator answers the call on the toll line by plugging the plug 500 of a cord circuit of her position into the toll line jack 501, thereby establishing a circuit from high resistance ground over the sleeves of jack 501 and plug 500, thence through non-inductive resistance 502 to battery and in parallel with such resistance through the windings of relays 503, 504 and 505 in series to battery. Due to the high resistance of the sleeve circuit of the toll trunk, marginal relays 503 and 504 do not operate, but relay 505 operates closing an obvious circuit for relay 506 which operates to transfer the tip of plug 500 from the busy test lead 507 of the associated position telephone circuit to the normal contacts of the ringing key 508. When now the operator throws the key 509 to its left or talking position, a talking circuit is established from the toll trunk over the tips of jack 501 and plug 500, the front contact of relay 506, the upper normal contacts of ringing key 508 and cord splitting key 510, the upper alternate left contacts of key 509, the inner upper right normal contacts of grounding key 511, conductor 512, the lower normal contacts of relay 600, conductor 513, the left windings of repeating coil 514, the non-inductive resistance 515, conductor 516, the upper normal contacts of

relay 606, conductor 517, the inner lower right normal contacts of grouping key 511, the lower left alternate contacts of key 509, the lower normal contacts of keys 510 and 508 over the rings of plug 500 and jack 501.

At the operator's telephone circuit, this circuit is inductively connected through the right winding of repeating coil 514, over the tips of headset jacks 518 and 519 and head-set plugs 520 and 521 through the headset transmitter 522 and is inductively connected to the headset receiver 523 over the sleeves of plug 520 and jack 518, the inner lower back contact of relay 524, through resistance 515, the lower left winding of repeating coil 514, the upper back contact of relay 524, and the rings of jack 519 and plug 521. The operator is now enabled to receive instructions over the toll line for terminating the connection.

It will be assumed that the connection is to be terminated in the dial switching office schematically disclosed in Fig. 4. The operator will first test the jacks of trunks extending to such office by touching the tip of cord plug 525 to the sleeves of such jacks. The sleeves of busy trunks will have battery potential connected thereto whereby a busy test circuit will be established extending from the tip of plug 525, over the back contact of relay 526, busy test lead 507, upper right normal contact of grouping key 511, through the winding of busy test relay 527 at the operator's telephone circuit to ground. Relay 527 will therefore operate connecting battery through the parallelly connected condenser 528 and resistance 529 through the primary winding of busy test coil 530 to ground whereby current is induced into the operator's headset receiver to produce a busy test click, over a circuit extending through the secondary winding of coil 530 over the inner lower back contact of relay 524, thence as traced through the headset receiver 523 and over the upper back contact of relay 524. When, however, the operator tests the jack of an idle trunk, relay 527 will not operate to produce a click in the headset receiver and thereupon the operator will insert the cord plug 525 into the idle trunk jack.

It will be further assumed that the idle trunk is the one disclosed in Fig. 4 as terminating in jack 450 at the toll operator's position and extending to the terminating office where it terminates in an incoming selector of the type schematically disclosed in the right portion of Fig. 4. Upon the insertion of the plug 525 into jack 450, a circuit is closed from ground over the sleeves of the jack and plug to battery through the winding of cord sleeve relay 531 which thereupon operates and closes an obvious circuit for relay 526, which thereupon operates to transfer the tip of plug 525 from its normal connection with busy test lead 507, into connection with the upper normally closed contacts of ringing key 532. A circuit is now established from ground through the upper winding of relay 403 over the upper back contact of relay 404, the upper left winding of repeating coil 405, tip conductor 451 of the interoffice trunk, tips of jack 450 and plug 525, the front contact of relay 526 through the upper winding of retard coil 533, winding of supervisory relay 534, lower winding of coil 533, rings of plug 525 and jack 450, ring conductor 452 of the interoffice trunk, lower left winding of repeating coil 405, the lower back contact of relay 404 to battery through the lower winding of relay 403. Relays 403 and 534 both operate in this circuit, but as previously described, relay 403 upon operating causes the operation of relays

410 and 404 whereby the loop supervisory circuit just traced is immediately opened to release relay 534. Relay 534 is therefore operated only momentarily at this time and without effect. After the loop circuit is opened, relay 403 is maintained operated locally over the front contact of relay 404 as previously described and causes the operation and locking of relay 414 to close a start circuit for a preselected idle link circuit such as is represented by the box 416.

The link circuit then proceeds to connect with the calling trunk, with an idle receiving circuit and with an idle sender. As previously described when an idle sender has been selected, relay 411 at the incoming selector is operated, to release relay 404 whereupon the loop circuit previously traced through the windings of relays 403 and 534 is reestablished. Relay 534 thereupon operates to close the circuit of supervisory lamp 535 as a signal to the operator that a sender has been seized and that she may proceed to key the number of the desired line. She first operates the cord key 510 to open the cord circuit toward the toll line and then operates the key-pulsing key 606 of her key-set circuit. Upon the operation of key 606 an obvious circuit is established from ground over the left contacts of key 606 through the winding of the key-pulsing relay 607 and through the non-inductive resistance 608 in parallel to battery and a second circuit is established from ground over the right contacts of key 606 through the winding of relay 600 and resistance 601 to battery and in parallel therewith over the inner upper normal contacts of relay 613 to battery through the winding of slow-to-release disconnect relay 612. Relays 600, 607 and 612 all operate, relay 612 locking under the control of relay 613 in a circuit from battery through its winding over the inner upper normal contacts of relay 613 to ground at the inner lower front contact of relay 612, and holding relay 600 operated over its inner lower front contacts following the release of key 606. When key 606 is released, relay 607 releases after a predetermined interval and with relay 612 locked operated establishes a circuit extending from battery through lamp 650 the lower contacts of relay 612 to ground over the back contact of relay 607 whereupon lamp 650 lights as a signal to the operator that she may proceed to key up the digits of the wanted line designation on the keys of her key-set 610.

During the period that relay 607 remains operated, key-pulsing signaling current of the two frequencies 1300 and 1700 cycles is transmitted from the signaling current supply circuit 650 over conductor 618, resistance 620, the lower contact of relay 607, the right windings of repeating coil 617, the inner lower contacts of relay 607, through resistance 621 and over conductor 619 to the supply circuit 650. This current is inductively transmitted over a circuit which may be traced from the upper terminal of the left windings of repeating coil 617, over the lower front contacts of relay 600, conductor 512, the inner upper right normal contacts of grouping key 511, the upper left alternate contacts of talking key 509, upper normal contacts of splitting key 536 and ringing key 532, thence as traced over the interoffice trunk circuit through the left windings of repeating coil 405 and returning over the lower normal contacts of keys 532 and 536, the lower left alternate contacts of key 509, the inner lower right normal contacts of grouping key 511, conductor 517 over the 75

upper front contacts of relay 600, to the lower terminal of the left windings of repeating coil 617. As before described the signaling current is further transmitted through the windings of repeating coil 405 to the receiving circuit 419.

After observing the lighted lamp 650, the operator proceeds to key the digits of the wanted line number in the manner previously described, following which she depresses the start key 642, 10 whereupon a circuit is established from ground over the right contacts of key 642 through the winding of start relay 613 and resistance 614 to battery. Relay 613 thereupon operates, closes a locking circuit for itself over its inner lower front contacts to ground over the inner lower front contacts of relay 612 and transfers the holding circuit of relay 612 to the control of key 642. This holding circuit may be traced from battery through the winding of relay 612, over the inner upper alternate contacts of relay 613 to ground over the left contacts of key 642. Relay 613 is thus maintained operated so long as the key 642 is held depressed, but upon the release of the key, releases after a predetermined interval in turn releasing relays 600 and 613. During the time 15 that relay 613 is thus operated, start signaling current of the two frequencies 1500 and 1700 cycles is transmitted from the supply circuit 650 over conductor 644, through resistance 645, over the upper front contacts of relay 613, through the right windings of repeating coil 617, over the lower front contacts of relay 613, through resistance 646 and conductor 647 to the supply circuit 650 and thence inductively to the receiving circuit. The operator's key-set circuit is now 20 restored to its normal condition. Since the invention does not concern the supervisory or other functions of the cord and position circuits, a further description thereof will not be given 25 herein.

Had the operator desired to key-pulse out over the toll cord plug 500, she would have followed the same procedure above described except that she would not have operated splitting key 510 but would have operated splitting key 536.

While the invention has been illustrated as applied to two specific types of toll positions it is to be understood that the fundamental features thereof are equally applicable to other types of toll or local positions for use in completing toll 30 and local calls.

What is claimed is:

1. In a telephone system, a cord circuit, and an operator's key-set circuit comprising digit keys, a key-pulsing key, a start key, a plurality of sources of signaling current, a first relay operable in response to the operation of said key-pulsing key to establish a signaling circuit from said key-set circuit to said cord circuit, a second relay operable following the operation of said key-pulsing key to associate one of said sources of signaling current with said signaling circuit as a signal that key-pulsing has been initiated, means effective upon the operation of said digit keys for selectively associating others of said sources of signaling current with said signaling circuit, a relay responsive to the operation of said start key for associating another of said sources of signaling current with said signaling circuit as a signal that key-pulsing has been completed, and means operative a predetermined interval following the restoration of said start key for releasing said relays to restore said key-set circuit to normal.
2. In a telephone system, a cord circuit and

an operator's key-set circuit comprising digit keys, a key-pulsing key, a start key, a plurality of sources of signaling current, a first relay operable in response to the operation of said key-pulsing key to establish a signaling circuit from said key-set circuit to said cord circuit, a second relay operable following the operation of said key-pulsing key to associate one of said sources of signaling current with said signaling circuit as a signal that key-pulsing has been initiated, a lamp signal operable following the release of said key-pulsing key and said second relay for indicating that the digits of a wanted line number may be keyed on said digit keys, means effective upon the operation of said digit keys for selectively associating others of said sources of signaling current with said signaling circuit, a relay responsive to the operation of said start key for associating another of said sources of signaling current with said signaling circuit as a signal that key-pulsing has been completed, and means operative a predetermined interval following the release of said start key for releasing said relays to restore said key-set circuit to normal.

3. In a telephone system, a cord circuit, an operator's telephone circuit and a key-set circuit comprising digit keys, a key-pulsing key, a start key, a plurality of sources of signaling current, a first relay operable in response to the operation of said key-pulsing key to disconnect said operator's telephone circuit from said cord circuit and to establish a signaling circuit from said key-set circuit to said cord circuit, a second relay operable following the operation of said key-pulsing key to associate one of said sources of signaling current with said signaling circuit as a signal that key-pulsing has been initiated, means effective upon the operation of said digit keys for selectively associating others of said sources of signaling current with said signaling circuit, a relay responsive to the operation of said start key for associating another of said sources of signaling current with said signaling circuit as a signal that key-pulsing has been completed and means operative a predetermined interval following the restoration of said start key for releasing said relays to restore said key-set circuit to normal.

4. In a telephone system, a cord circuit, and a key-set circuit comprising digit keys, a key-pulsing key, a plurality of sources of signaling current, a first relay operable in response to the operation of said key-pulsing key to establish a signaling circuit from said key-set circuit to said cord circuit, a second relay operable during the operation of said key-pulsing key and for a predetermined interval following the release of said key to associate one of said sources of signaling current with said signaling circuit as a signal that key-pulsing has been initiated, a start relay, a slow-to-release relay operable in response to the operation of said key-pulsing key to lock itself operated under the control of said start relay and to hold said first relay operated following the release of said key-pulsing key, means effective upon the operation of said digit keys for selectively associating others of said sources of signaling current with said signaling circuit, and a start key effective upon its operation for operating said start relay to associate another of said sources of signaling current with said signaling circuit as a signal that key-pulsing has been completed and for transferring the locking circuit of said slow-to-release relay to the control of said start key, said start relay upon operating

locking under the control of said slow-to-release relay whereby upon the release of said start key, said slow-to-release relay in turn releases said other relay to open said signaling circuit.

5. In a telephone system, a first office, a second office, a trunk interconnecting said offices, a cord circuit at said first office for connection with said trunk, signal receiving equipment at said second office associative with said trunk, a key-set circuit associative with said cord circuit comprising digit keys, a key-pulsing key, a start key, a plurality of sources of signaling current, a first relay operable in response to the operation of said key-pulsing key to establish a signaling circuit from said key-set circuit to said receiving equipment, a second relay operable in response to the association of said receiving equipment with said trunk for associating one of said sources of signaling current with said signaling circuit as a signal that key-pulsing has been initiated, means effective upon the operation of said digit keys for selectively associating others of said sources of signaling current with said signaling circuit, a relay responsive to the operation of said start key for associating another of said sources of signaling current with said signaling circuit as a signal that key-pulsing has been completed, and means operative a predetermined interval following the restoration of said start key for releasing said relays to restore said key-set circuit to normal.

6. In a telephone system, a first office, a second office, a trunk interconnecting said offices, a cord circuit at said first office for connection with said trunk, signal receiving equipment at said second office associative with said trunk, a key-set circuit associative with said cord circuit comprising digit keys, a key-pulsing key, a plurality of sources of signaling current, a first relay operable in response to the operation of said key-pulsing key to establish a signaling current from said key-set circuit to said receiving equipment, a key-pulsing relay, a first slow-to-release relay operable in response to the operation of said key-pulsing key to lock itself operated under the control of said key-pulsing relay and to prepare an operating circuit for said key-pulsing relay, a start relay, a slow-to-release disconnect relay operable in response to the operation of said first slow-to-release relay to lock itself operated under the control of said start relay and to hold said first relay operated, means operable upon the association of said receiving equipment with said trunk to complete the operating circuit of said key-pulsing relay whereby said key-pulsing relay releases said first slow-to-release relay which in turn releases said key-pulsing relay and whereby, during the interval that said key-pulsing relay is maintained operated, one of said sources of signaling current is associated with said signaling circuit as a signal that key-pulsing has been initiated, means effective upon the operation of said digit keys for selectively associating others of said sources of signaling current with said signaling circuit, and a start key effective upon its operation for operating said start relay to associate another of said sources of signaling current with said signaling circuit as a signal that key-pulsing has been completed and for transferring the locking circuit of said disconnect relay to the contacts of said start key, said start relay upon operating, locking under the control of said disconnect relay whereby upon the release of said start key, said disconnect relay releases after an interval in turn releasing said first relay

and said start relay to open said signaling circuit.

7. In a telephone system, a cord circuit having front and rear sections and an operator's key-set circuit comprising digit keys, a front cord key-pulsing key, a rear cord key-pulsing key, a start key, a plurality of sources of signaling current, a first relay operable in response to the operation of said front cord key-pulsing key for establishing a signaling circuit from said key-set circuit to the front section of said cord circuit, a second relay operable in response to the operation of said rear cord key-pulsing key for establishing a signaling circuit from said key-set circuit to the rear section of said cord circuit, a 15 third relay operable following the operation of

said key-pulsing key to associate one of said sources of signaling current with said signaling circuit as a signal that key-pulsing has been initiated, means effective upon the operation of said 5 digit keys for selectively associating others of said sources of signaling current with said signaling circuit, a relay responsive to the operation of said start key for associating another of said sources of signaling current with said signaling circuit as a signal that key-pulsing has been completed and means operative a predetermined 10 interval following the restoration of said start key for releasing said relays to release said key-set circuit to normal.

JAMES B. MCKIM.
